UNITED STATES PATENT OFFICE.

CORRY B. COMSTOCK, OF NEW YORK, N. Y.

INSULATING MEANS FOR BAKE-OVENs.

1,156,390.

Specification of Letters Patent.

Patented Oct. 12, 1915.

Application filed October 8, 1913. Serial No. 784,142.

To all whom it may concern:

Be it known that I, CORRY B. COMSTOCK, a citizen of the United States, residing at New York, in the county of New York and State of New York, have invented certain new and useful Improvements in Insulating Means for Bake-Ovens, of which the following is a specification, reference being had therein to the accompanying drawing.

10 The principal object of the invention is to provide an insulating supporting means adapted to be positioned underneath a bake oven of any usual or preferred type and to serve to prevent the transmission of heat 15 from the oven downward to the floor or other support upon which the oven as a whole rests.

The above stated object is attained by means of the devices which will be described 20 in the following specification.

In the accompanying drawings I have shown the embodiment of my invention which I now deem preferable, but it will be understood that many changes and modifications may be made within the scope of the appended claims without departing from the spirit of my invention.

Of the drawings—Figure 1 is a sectional plan view taken along the line 1—1 of Fig. 30 2; Fig. 2 is a vertical sectional view taken along the line 2—2 of Fig. 1; Fig. 3 is a vertical sectional view taken along the line of Fig. 3—3 of Fig. 1; Fig. 4 is a vertical sectional view taken along the line 4—4 of Fig. 1; and Fig. 5 is a vertical sectional view taken along the line 5—5 of Fig. 1.

Referring to the drawings 1 represents as a whole a floor upon which the bake oven is to be supported. As shown in the drawings the floor is formed of concrete and is provided with a series of transverse and longitudinal supporting beams integrally formed with the body of the floor.

45 The bake oven as a whole is diagrammatically indicated at 2, and as the oven can be of any usual or preferred type a detailed description of it is unnecessary. It is sufficient to point out that it comprises a main central chamber 2^a adapted to serve as a combustion space, and two side flues 2^b—2^b adapted for the passage of hot gases. The central opening 2^a extends downward along a part of its length to form the ash pit 2^c.

50 Interposed between the main bottom part of the furnace or oven 2 and the floor 1 is the insulating means to which my invention

primarily relates. This is constructed as follows: In a layer of grouting 3 on the floor there are placed a number of parallel longitudinal rows of hollow tiles 4 arranged with their open ends communicating with each other so as to form a series of continuous ducts or passageways 5 extending longitudinally of the furnace. The ducts at the sides of the ash pit extend substantially the 60 full length of the furnace while those in the center terminate at one end near the rear end of the ash pit. At the rear end of the furnace the ducts 5 terminate in a continuous transverse passage 6 which extends the 65 entire width of the furnace. This passage is bounded at its outer side by means of the brick wall 7 and is closed at its ends in any suitable way. At the other end of the furnace and at opposite sides of the ash pit are 70 other transverse passages 8, 8 which are similar to the passage 6. They are bounded at their outer sides by the brick wall 9 and are suitably closed at their ends. Adjacent the inner end of the ash pit is another transverse passage 10 similar to the passages 8, 8. Communicating with each of the passages 8, 8 and 10 are ducts 11, 11 which extend downward through the floor into the room underneath. Communicating with the 75 transverse passage 6 are ducts or flues 12, 12 which extend upward and are preferably carried outward and embedded in the vertical partition wall 13. These ducts 12, 12 can extend to a chimney or any other desired 80 place of discharge.

Upon the tops of the hollow tiles 4 there is placed a layer 14 of asbestos preferably in the form of boards or sheets. Upon the asbestos layer 14 there are placed a series of 85 hollow tiles 15 arranged with their openings 90 extending vertically. The open spaces within the tiles are filled with some substance 16 such as mineral wool which is a poor conductor of heat. Upon the tops of the tiles there is placed another layer 17 of asbestos 95 and upon this top asbestos layer there is built a concrete slab 18 which serves to support the furnace or oven.

It will be seen that when the oven is in 100 operation the heat which is conducted downward and given off at the bottom is largely stopped in transmission by means of the asbestos layer 17, and mineral wool packing 105 16, and the asbestos layer 14. But even with 110 these several insulating means, some heat will still find its way downward and in

order to absorb this and carry it away I provide the free air spaces which have been described. It will be seen that there is a continuous passageway for air through the 5 ducts 11, the transverse passages 8, 8 and 10, the longitudinal ducts 5, the transverse passage 6 and the upright ducts 12, 12. The air in the ducts 5, 5 will absorb heat transmitted downward from the furnace and as 10 this air becomes heated it will pass outward and upward through the ducts or flues 12, permitting fresh cool air to enter through the ducts 11. In this way continuous currents of air are caused and the heat is all 15 absorbed and carried upward through the ducts 12, 12 instead of being permitted to pass downward through the floor 1 into the room beneath.

It is usual in the construction of bakeries 20 to locate the bread room directly underneath the ovens and on this account it is especially desirable to protect the room from excess heat derived from the oven. Furthermore, the insulation of the oven from the other 25 parts of the building is very advantageous as, without such insulation, the heat generally causes more or less serious cracks in the building walls on account of expansion.

What I claim is:

- 30 1. In a heat insulating means for bake ovens, the combination of a plurality of parallel horizontal ducts adapted to lie underneath the oven, means forming a transverse passage connecting the ducts at one end, other means forming a transverse passage connecting the ducts at the other end, means for admitting air to the first said passage, and flues for receiving air from the second said passage and conducting it upward.
- 35 2. In a heat insulating means for bake ovens the combination of a plurality of parallel horizontal ducts adapted to lie underneath the oven the center ducts being shorter than those at the sides and all of the ducts terminating at one end in the same transverse vertical plane, means forming a transverse passage connecting the ducts at the last said end, other means forming a plu-

rality of transverse passages respectively connecting the longer side ducts, and the 50 shorter center ducts, means for admitting air to the last said passages, and flues for receiving air from the first said passage and conducting it upward.

3. In a supporting and heat insulating 55 means for bake ovens, the combination of a plurality of hollow tiles set on end and adapted to lie underneath the oven, and a packing substance within the open spaces of the tiles for resisting the transmission of 60 heat.

4. In a supporting and insulating means for bake ovens, the combination of a plurality of hollow tiles set on end and adapted 65 to lie underneath the oven, a packing substance within the open spaces of the tiles for resisting the transmission of heat, a layer of heat insulating material above the tiles, and a layer of heat insulating material 70 below the tiles.

5. In a heat insulating means for bake ovens, the combination of a plurality of parallel horizontal ducts adapted to lie underneath the oven, means for admitting air to each of the ducts at one end, flues for receiving air from each of the ducts at the other end and conducting it upward and a heat insulating means above the said ducts and interposed between them and the oven. 75

6. In a heat insulating means for bake 80 ovens, the combination of a plurality of parallel horizontal ducts adapted to lie underneath the oven, means for admitting air to each of the ducts at one end, flues for receiving air from each of the ducts at the 85 other end and conducting it upward, a plurality of hollow tiles set on end above the said ducts, and a packing substance within the open spaces of the tiles for resisting the transmission of heat. 90

In testimony whereof, I affix my signature in presence of two witnesses.

CORRY B. COMSTOCK.
